UNITED STATES PATENT OFFICE

CARL HOFMANN, OF BERLIN, GERMANY

STRETCHING AND SMOOTHENING DEVICE FOR NECKTIES

Application filed January 6, 1928, Serial No. 244,832, and in Germany November 28, 1927.

This invention relates to a stretching and smoothening device for neck-ties and has for its general object to provide a device of this kind by means of which it will be possible to 5 easily and conveniently stretch and smoothen out neck-ties in order to remove the wrinkles which are produced during wearing the same.

The device according to my invention consists essentially of an oblong strap with 10 slightly tapering longitudinal edges, said strap being made from paper-board, wood, metal, galalith, hard-rubber or similar material and having one or both of its surfaces 15 slightly roughened. In order to stretch and smoothen out a neck-tie which may have become wrinkled during wearing the same, the wrinkled tie is merely pulled over the stretching device after said slightly roughened surface or surfaces have been slightly 20 wetted. Thus, for instance, the tie which is taken off at night may be pulled over said slightly wetted device and again be put on in perfectly smooth condition with all wrinkles 25 removed therefrom.

The stretching and smoothening effect which is exerted on the tie by said device will be greatly improved according to my invention by providing said slightly roughened 30 surface or surfaces on the strap. For this purpose a great number of fine grooves or the like may be provided on said surface or surfaces. The roughened surface of the stretching device if wetted by means of a wet towel 35 or sponge will now easily retain a certain small amount of moisture which will essentially enhance the effect of stretching and smoothening of the tie.

The two parts of the strap, moreover may 40 be connected with each other by means of a hinge or hinges, said hinge or hinges permitting to fold one part flat upon the other. In this case on either side of the hinge small locking straps may be provided by means of 45 which said hinge may be locked in unfolded condition of the device.

In the accompanying drawing I have shown two examples of construction of my new stretching and smoothening device for 50 neck-ties. Fig. 1 shows my new stretching

and smoothening device in its most simple form, while Fig. 2 shows a further modified form comprising a strap made of two or more parts which are properly connected by a hinge permitting the device to be folded together.

Referring now more particularly to the drawing, Fig. 1 shows the stretching and smoothening device in the form of a plain flat strap of oblong conformation with slightly tapering longitudinal edges, which strap may be made from paper-board, wood, metal, galalith, hard-rubber or similar material. According to my invention the strap is provided at its front part on one or both of its surfaces with a greater number of fine grooves, recesses or the like, indicated at *a* in Figs. 1 and 2. According to Fig. 2 the stretching and smoothening device is made in two parts *b* and *c* which are connected with each other by a hinge *e* permitting folding and unfolding the device. The hinge *e* is further provided according to my invention with locking members *f* and *g* which serve for locking the device when in unfolded condition, thus keeping the two members *b* and *c* of the device in straight condition ready for being inserted into a tie.

I claim:

A stretching and smoothening device for 80 neck-ties, consisting of an oblong strap having tapering longitudinal edges following the conformation of a tie and permitting said device to be inserted into a tie for stretching and smoothening the same, at least one surface of said strap being slightly roughened to retain only a small amount of moisture, substantially as described and for the purposes set forth.

In testimony whereof I affix my signature. 85
CARL HOFMANN.
